TITUS S. EMERY, OF PHILADELPHIA, PENNSYLVANIA.

Letters Patent No. 102,929, dated May 10, 1870.

IMPROVEMENT IN BRICK-MACHINES.

The Schedule referred to in these Letters Patent and making part of the same.

I, TITUS S. EMERY, of Philadelphia, county of Philadelphia, State of Pennsylvania, have invented a Machine for Making Press-Bricks, of which the following is a specification.

Nature and Object of the Invention.

The object of my invention is to render automatic the hand-presses which are in common use for manufacturing press-bricks; and

My invention consists principally in arranging a number of such presses radially upon a horizontal disk or plate, to which an intermittent rotary motion is imparted, the several parts of each press being operated automatically, as the disk rotates, in a manner which will be fully described hereafter.

Description of the Accompanying Drawing.

Figure 1, sheet 1, is a vertical sectional view of my machine for making press-bricks;

Figure 2, a side elevation of a portion of the same;

Figure 3, a plan view;

Figures 4 and 5, sectional plans of the upper portion of the machine;

Figure 6, sheet 2, a plan view of the bed-plate, with part of the frame in section; and

Figures 7 and 8, views of an ordinary hand-press, arranged to be operated automatically, in accordance with my invention.

General Description.

The frame of the machine consists, in the present instance, of a bed-plate, A, of uprights and side braces B, secured to the same and connected together by cross-pieces, and of a horizontal frame, C, attached to the uprights, and arranged to support the upper portion of the machine.

The vertical driving-shaft D turns in suitable bearings in the frame C, and is furnished with a driving-pulley, a, and with a toothed pinion, b, which gears into a cog-wheel, b', of a vertical spindle, E, the latter also turning in bearings provided for it on the frame C.

The lower end of the driving-shaft D is reduced in diameter, and extends downward into a clay-tempering hopper or mill, F, which is suspended from the bottom of the frame C, the shaft within the hopper being provided with agitators or knives c and with a forcing-screw, e; but, as this portion of the machine forms no part of my present invention, it can be altered or modified to any desired extent.

The spindle E is furnished, at a point beneath its cog-wheel b', with an adjustable arm, d, (figs. 1 and 4,) which is arranged at each revolution of the spindle to strike one of a number of pins d', which project from the upper face of a disk, G, secured to the top

of a vertical shaft, H, the latter having its bearings in the step e of the bed-plate, and in the frame C at a point beneath the disk G.

The pins d' are, in the present instance, six in number, and are arranged in a circle upon the disk G so that they may be struck and turned successively by the arm d, the said disk and shaft H making, consequently, but one revolution for every six revolutions of the spindle E.

I is a horizontal disk or circular plate, secured to the shaft H in any suitable manner, and arranged to support a number of separate and independent brick-presses J J J, &c., which are suspended beneath the said disk, so that they may turn with the same and with the shaft H, as will be readily understood on reference to figs. 1, 2, and 3.

These presses are arranged radially upon the disk I, close to the periphery of the same, and at regular distances apart from each other, they being, in the present instance, six in number, to correspond with the number of pins d', and dividing the surface of the disk into six equal sections.

These presses, it should be understood, are precisely similar to those in common use for making press-bricks by hand, the main object of my invention being to render such presses automatic in their action; but, in order to fully understand the operation of the complete machine, it will be necessary to describe the construction of the presses, views of which, drawn to an enlarged scale, are shown in figs. 7 and 8.

Each press consists of opposite side frames e e, firmly secured to the disk I, and connected together at the bottom by a bar, e'.

A mold, f, of the same length and width as the brick which is to be made, is formed in the outer rim f' of the disk I, at a point between the side frames e e of each of the presses, these molds, as the disk is rotated, being brought one at a time beneath the lower open end of the hopper F, to receive their charge of clay, as will be hereafter described.

A vertical die or plunger, g, is arranged to slide in each mold f, the lower end of this plunger (furnished with a suitable anti-friction roller) being supported by the short arm of a lever, h, which, under the circumstances described hereafter, rests upon the bar e'.

The lever h has its fulcrum in a pin, h', which projects through, and is arranged to slide vertically in slots formed in the opposite side frames e e, and the long arm of the said lever is connected by a link, i, to an arm, i', of a rock-spindle, j, which turns in the side frames e e.

The plunger g, besides being operated by the lever h, is also acted on by an arm, k, hung to the

side frames, and connected by a rod, *k*, to a lever, *l*, the latter having at its outer end a roller, *l*', which, as the disk *I* rotates, travels upon the bed-plate *A*, and mounts an inclined or stationary cam, *m*, formed on the latter, this elevating the lever *l*, and causing the plunger *g* to rise upward through the mold *f*. The cap *p*, by which the top of each mold is covered, is connected by rods *q* to the sliding fulcrum *k*' of the lever *h*, and the latter and the rock-spindle *j* are so turned by means of a rod, *r*, furnished at its outer end with a roller, *r*', which traverses a stationary cam, *r*², of the bed-plate, that both the plunger and cap *p* may be drawn simultaneously, or nearly so, toward each other, to impart the required pressure to the brick.

The automatic throwing back of the cap *p* from the mold, after the brick has been pressed, is effected by a rod, *s*, secured to the cap, and arranged to strike and to be turned by a cam-like plate, *s*', secured to the frame *C*.

The rod *s* also serves as a medium for pushing the cap forward over the mold, after the latter has been filled with clay, it being operated at the proper moment by a swinging arm, *t*, under the control of a bell-crank lever, *t*¹, which is maintained in such a position by a spring, *t*², that it may be struck and turned by a pin, *u*, on the under side of the cog-wheel *b*'.

Operation.

Motion having been imparted to the driving-shaft, is transmitted, through the gearing described, to the shaft *H* and disk *I*, the intermittent motion in the direction of the arrow, which is thus imparted to the latter, permitting each of the presses to remain directly beneath the mill *F* for a sufficient time to enable its mold to be completely filled with clay, the latter being either dry or tempered, according to circumstances.

As soon as the mold of one of the presses has been filled, the disk *I*, by the action of the arm *d* upon one of the pins *d*', is moved to the extent of one-sixth of a revolution, or until the next press is brought beneath the hopper.

During this partial movement of the disk the cap *p* of the first press remains thrown back for a sufficient interval to enable the upper face of the brick in the mold to be dusted with sand or loam by an attendant, but, during the last portion of the movement, the cap is thrown forward so as to cover the mold, by means of its rod *s*, which is struck by the vibrating arm *t*, the latter being turned by the spring lever *t*¹, which is operated by the pin *u* of the cog-wheel *b*', (see figs. 3 and 5).

The first press has now reached the position indicated by the number 2 in fig. 3, and at the next partial revolution of the disk it is moved to the third position, the brick within the mold receiving, during this latter movement, the requisite degree of pressure between the plunger *g* and cap *p*, as I will now proceed to describe.

At the beginning of the third movement the roller *r*', at the outer end of the rod *r*, gradually ascends the incline *r*², until the said rod assumes the elevated position shown in fig. 7. This will depress the long arm of the lever *h*, and cause its short arm to be correspondingly elevated, which movement, by exerting an upward movement on the plunger *g*, will cause a depression of the sliding fulcrum *k*', and a consequent binding of the cap *p* upon the top of the mold during said upward pressure of the plunger.

After the brick has been thus pressed in the mold, and before the completion of the third movement of the disk, the rod *r* descends the abrupt portion of the incline *r*², and again rests upon the bed-plate, this having the effect of lowering the plunger *g*, and of

slightly raising the cap *p* above the mold, so that it may be readily thrown back from the same.

While the press is being moved from the third to the fourth position, the cap is thrown back from the mold by the cam-like plate *s*', with which the rod *s* of the said cap is brought in contact, the several parts of the press being now in the position shown on the left-hand side of fig. 1.

During the next movement of the disk, and while the press is being brought to the fifth position, (fig. 3) the roller *l*' of the arm *l* traverses the incline *m*, and thereby raises the said arm, the latter, through the medium of the rod *k*' and arm *k*, elevating the plunger *g* to its full extent, so as to raise the brick out of the mold.

The brick is removed by an attendant, and another attendant wipes off the mold, before the descent of the plunger; or, as is to be preferred, this wiping can be effected automatically.

During the sixth movement of the disk the arm *l* passes the incline *m*, and is depressed so that the plunger *g* again descends to its former position, and before the press again passes beneath the hopper, to receive a second charge of clay, the interior of the mold should be dusted (either automatically or by an attendant) with loam or fine sand.

Each of the presses with which the disk is furnished is complete in itself, and is operated automatically in precisely the same manner as the first, the movements of the several parts of each press being conducted precisely as in the hand-machine, but with much greater rapidity and regularity.

Although I have described the disk as being adapted for six presses, any greater or less number can be arranged upon the same, and it is not necessary that the bricks made by the several presses should be of the same size or shape, and two, three, or even a greater number of molds can, if desired, be arranged side by side in the same press.

The adjustability of the arm *d*, by which the disk is driven, forms an important feature of my invention, as, by lengthening or shortening the said arm, the point at which the disk will stop after each revolution can be regulated with the greatest nicety, this enabling the effects of wear, &c., upon the machine to be readily overcome.

In some cases the intermediate cog-wheel *b*' and its spindle *E* can be dispensed with, and power transmitted directly from the driving-shaft to the shaft *H*.

It will be evident, without further description, that by arranging a number of the within-described presses upon a rotating disk, *I*, and thus rendering their movement entirely automatic, bricks fully equal to the hand-made article can be produced with great rapidity, and without requiring the skilled labor that is usually demanded in the manufacture of pressed bricks.

It should be understood, however, that I do not desire to claim broadly a brick-machine in which molds are formed in a rotating disk, but merely the arrangement, upon a rotating disk or plate, in such a manner that they can be operated automatically, of the within-described complete hand-presses, which have been found in practice to be the best adapted for the production of press-bricks; therefore, instead of the cam-plate *s*', pin *u*, arms *t* and *t*¹, and inclines *r*² and *m*, other well-known mechanical devices and movements, operating in a like manner, may be employed.

Claims.

1. The presses *J*, each provided with a mold, *f*, vertical plunger *g*, lever *h*, and hinged cap *p*, and arranged radially on the disk or plate *I*, in combination with mechanism, substantially as described, whereby the operating parts of each press are rendered automatic.

2. The disk *I*, its presses *J*, shaft *H*, and pins *d* and *d*'.

&c., in combination with the shaft E and its pin or arm d, operating as set forth.

3. The arm d, fitted to a slot in the shaft E, and adjustable therein, for the purpose specified.

4. The combination, substantially as herein described, of the rod s of the cap p, carried by arms jointed below the mold f', vibrating arm t, spring lever t', and pin u of the wheel b', whereby the said cap may be thrown forward over the mold f'.

5. The combination, substantially as herein described, of the rod s of the cap p with the stationary cam-plate s', for throwing back the cap from the mold.

6. The combination of the arm r, hung to the rock-

spindle j, with the stationary cam r', for operating those parts which impart the required degree of pressure to the brick.

7. The combination of the lever k, rod k', arm l, and stationary incline m, for the purpose of elevating the plunger g, to eject the finished brick from the mold.

In testimony whereof I have signed my name to this specification in the presence of two subscribing witnesses.
